UNITED STATES PATENT OFFICE.

SHIKER M. DEBAKEY, OF LAKE CHARLES, LOUISIANA.

SHOW-CASE.

1,337,049.

Specification of Letters Patent. Patented Apr. 13, 1920.

Application filed August 26, 1919. Serial No. 319,978.

To all whom it may concern:

Be it known that I, SHIKER M. DEBAKEY, a citizen of the United States, residing at Lake Charles, in the parish of Calcasieu and 5 State of Louisiana, have invented certain new and useful Improvements in Show-Cases; and I do hereby declare the following to be a full, clear, and exact description of the invention, such as will enable others 10 skilled in the art to which it appertains to make and use the same.

The present invention relates to improvements in show cases, and has for an object to provide an improved show case adapted to 15 give the customer quick service and whereby the customer may serve himself; and which disposes of the necessity for the customer going through the formality of asking the clerk for the particular commodity desired.

20 In accordance with the present invention the commodities are displayed on a movable display carrier or table, which is provided with means accessible to the customer for moving the carrier into a position which admits of the customer serving himself when 25 a door in the show case is thrown open by means accessible only to the clerk behind the case.

20 In the accompanying drawings forming a part of this application, and in which similar reference symbols indicate corresponding parts in the several views:

Figure 1 is a top plan view of an improved show case constructed in accordance 35 with the present invention.

Fig. 2 is a vertical central sectional view through the same, showing certain parts in dotted line positions.

Fig. 3 is a horizontal sectional view taken 40 on the line 3-3 in Fig. 2; and

Fig. 4 is a vertical sectional view taken from the opposite side as compared with Fig. 2.

Referring more particularly to the drawings, the improved show case consists of a base 1 having supported thereon a case indicated generally at 2, and being composed for the most part of glass to admit of inspection by customers of the commodities 45 placed therein. A step or bearing 3 is mounted centrally within the case 2 on the base 1, and receives the journal of a vertical shaft 4 having a shoulder 5 on which rests a table or carrier 6. Above the table 6 is a

superstructure 7 supporting price tags 8 and 55 receptacles 9 for containing water to keep the air within the case at a proper humidity.

The shaft 4 extends up through the top 10 of the case which is also preferably of glass, so as to allow the customer to look down 60 upon the commodities displayed on the table or carrier 6, and above the glass top 10 such shaft 4 is provided with a hand wheel 11 accessible alike to the customer and clerk. If desired a mirror 12 may be supported on 65 the hand wheel 11.

Horizontally swinging doors 13 are provided to give access to the lower portion of the case 2 below the table or carrier 6, this lower portion of the case constituting a 70 space for reserve stock, to which the clerk may have recourse from time to time to replenish the articles sold from the table or carrier 6.

Above the horizontally swinging doors 13 75 is a vertically swinging door 14 pivoted at its lower edge, as indicated at 15, and adapted to swing down to the position shown in dotted lines in Fig. 2 or shown in full lines in Fig. 3. A catch 16 provides for holding 80 the door 14 in the closed position.

At the opposite side of the case a similar vertically swinging door 17 is arranged to swing down on pivots 18 to the dotted line position shown in Fig. 2 or the full line 85 position shown in Fig. 3.

By reference to Figs. 2 and 3 it will be seen that the doors 14 and 17, when in their lowered positions, extend substantially in a plane with the table or carrier 6, and these 90 doors, when open, give access to such table or carrier from both the front and rear of the show case.

A pad 19 is affixed to the inside of the door 17 near one edge thereof, and this pad is 95 adapted to be struck by the lower end of a pivoted trigger or lever 20 connected to be operated by a horizontally reciprocating rod 21 having an eye 22 at its rear end which is accessible to the finger of the clerk, by which he may pull the rod 21 rearwardly to the dotted line position shown in Fig. 4, thus causing the trigger or lever 20 to be rocked to the dotted line position, which will cause the lower end thereof to strike the pad 19 100 and throw the door 17 outwardly. A coil spring 20' causes the return of the pivoted trigger 20 to the full line normal position. 105

The door 17 being thrown out of its position of equilibrium will descend by its weight to the horizontal position, where it extends in substantially the same plane with the table or carrier 6 and allows access by customers to the table 6, while also providing a shelf on which articles may be temporarily laid after removal by the customer from the table or carrier 6.

- 10 A chain or cord 23 is connected at one end to the door 17, as indicated at 24, and is guided through one or more eyes 25; such cord passing through the rear wall of the case 2 and having a button 26 intended for 15 the grasp of the clerk, whereby the door 17 may be lifted to its closed position by pulling upon the cord 23. The door 17 is therefore under the complete control of the clerk behind the counter, who may cause the same 20 to open and subsequently close the same at pleasure.

In use the single embodiment of the invention shown in the drawings is arranged to be presided over by a single clerk, who 25 stands behind the case and has access to the doors 13 and 14. The customer at the front of the case may look through the glass top 10 and inspect the commodities displayed on the table or carrier 6, and after selection of 30 any particular commodity is made, the customer himself, without having recourse to the clerk, may rotate the table or carrier 6 by means of the hand wheel 11 which projects above the top of the case, until the selected article is brought to a position opposite the door 17.

This inspection of the articles and the selection of the desired article is all made 40 without the necessity of making any inquiries of the clerk, and the clerk will be on the alert so that when a customer rotates the table or carrier 6 in the manner above described, such clerk will pull upon the eye 22 of the operating rod 21 and cause the trigger 45 20 to throw the door 17 open. The customer is then able to reach into the case and remove the selected article from the table or carrier 6.

The door 17, in the horizontal open position, forms a shelf on which the removed article may be temporarily placed while the customer is engaged in paying for same.

After the purchase has been completed and the customer has departed, the clerk may 55 draw upon the knob 26, and through the cable or chain 23 draw the door 17 back into the closed position.

As articles are removed from the table or carrier 6, the clerk may replenish same by 60 having recourse to the reserve stock carried in the lower portion of the case beneath such table 6, and for this purpose he opens both the doors 13 and 14, as indicated in dotted lines in Fig. 2. The door 14 also 65 forms a shelf on which the articles may be

laid after removal from the reserve stock space prior to their arrangement on the table 6. The hand wheel 11 is equally accessible to the clerk for the purpose of rotating the table to bring the empty spaces 70 thereon to the rear of the counter where he may supply them with fresh articles.

It is obvious that those skilled in the art may vary the details of construction and arrangements of parts without departing from 75 the spirit of my invention, and therefore I do not wish to be limited to such features except as may be required by the claims.

I claim:

1. An improved show case having transparent portions and doors in the front and rear thereof, a movable carrier in said case adapted to contain articles viewable through the transparent portion and accessible through said doors, means accessible alike 80 to both customer and clerk for moving said carrier, one of said doors being accessible to the clerk for replenishing articles sold from said carrier, the other of said doors being accessible to the customer for removing articles from the carrier and being openable by the clerk, substantially as described.

2. An improved show case, a carrier in the show case for containing commodities to be sold, said carrier being supported above 95 the base of the show case whereby to provide between the same and such base a space for reserve stock, doors in the show case giving access to the reserve stock space and said carrier, means whereby a customer may 100 move the carrier to bring a selected article opposite one of such doors, and means under the control of the clerk whereby the latter door may be thrown open to allow the customer to remove the selected article, substantially as described.

3. An improved show case having glass panels therein, a vertical shaft in said show case, a rotating table carried by said shaft and spaced from the bottom of said show 110 case to provide a space for reserve stock below same, said table adapted to contain commodities to be sold, doors at the rear of the show case giving access to the reserve stock space, vertically swinging doors at the front 115 and rear of said show case adapted to swing down in substantially the same plane with said table, a hand wheel on the upper end of said shaft above the top of the case and accessible alike to both customer and clerk for 120 rotating the table, means whereby the swinging door at the front of the case may be opened by the clerk at the rear of the case, and other distinct means whereby the clerk at the rear of the case may close the 125 swinging door at the front of the case, substantially as described.

4. An improved show case, a movable carrier therein adapted to contain commodities to be sold, a door pivoted at its lower edge 130

and adapted to swing vertically down to a substantially horizontal position adjacent said carrier, a pivoted trigger adapted to strike said door to force it out of its closed position and out of its position of equilibrium, means accessible only at the rear of the case for operating said trigger, means

whereby such door may be closed, and means for moving such carrier to bring articles opposite the door for removal by a customer 10 when the door is opened by a clerk in the rear, substantially as described.

SHIKER M. DEBAKEY.
